UNITED STATES PATENT OFFICE

JAKOB BURKHARDT, OF DETROIT, MICHIGAN, ASSIGNOR TO THIRD DIMENSION PICTURES, INC., OF NEW YORK, N. Y.

APPARATUS FOR TINTING MOTION PICTURE FILMS AND THE LIKE

Application filed December 18, 1929. Serial No. 414,938.

The main objects of this invention are:

First, to provide a machine or apparatus for tinting motion picture films and the like whereby one longitudinal section or portion 5 of the film may be tinted with one color and another longitudinal section with another color.

Second, to provide an apparatus for the tinting of films which is automatic in operation and of very large capacity.

Objects pertaining to details and economies of my invention will definitely appear from the description to follow. The invention is defined in the claims.

A structure embodying the features of my invention is clearly illustrated in the accompanying drawings, in which:

Fig. 1 is an end elevation with parts broken away to better disclose the structure.

Fig. 2 is a fragmentary plan view.

Fig. 3 is a fragmentary view mainly in vertical section on line 3—3 of Fig. 2.

Fig. 4 is a conventionalized perspective view illustrating the film supporting pulleys.

Fig. 5 is a fragmentary view of the film of which both the longitudinal foreground and background sections are indicated as colored or tinted.

I have illustrated my improvements in a machine especially designed for the tinting of films such as are illustrated in my application for Letters Patent Serial No. 393,368, filed September 18, 1929, in which the film 30 comprises a series of background pictures and a series of image pictures disposed transversely of the film in coacting or associated pairs.

The frame 1 is of suitable character to support the parts and is provided with a bed or top 2. The dye or color tank 3 is removably supported on the top 2. A frame or support 4 for the immersing pulleys 5 is pivotally mounted on the brackets 6 by means of the pivot rod 7. The spindles 8 of the immersing pulleys are mounted on the swinging end of the frame and supported at an angle preferably in an inclined relation to the surface of the coloring liquid indicated at 9 in Fig. 3.

The frame carrying these immersing pulleys

may be raised from or lowered into the tank by means of the screws 10 swivelled in the cross piece 11 on the brackets and having threaded engagement with a cross piece 12 on the frame. The cross pieces 11 and 12 are journaled or pivoted for rocking movement on the brackets and frame respectively to permit the swinging of the frame.

The rests 13 are threaded into the cross piece 14 on the outer end of the support 4 to coact with the bottom of the tank. Lock nuts 15 are provided for holding these rests in adjusted position. These rests support the immersing pulleys in accurate relation to the surface of the coloring liquid.

The immersing rollers are provided with peripheral ribs 16 at each end having sprocket teeth 17 adapted to engage the feed perforations of the film.

The supply spindle 18 for the film indicated at 19 is mounted on an arm 20 on the immersing roller support. A supporting disk 21 is provided in coacting relation with the spindle. A friction brake or drag designated generally by the numeral 24 is provided for the supply or work spindle. The details of this are not illustrated.

The tank 3 is provided with an overflow 25 delivering to the supply reservoir 26, the liquid level being maintained in the tank 3 by means of a pump 27. The plunger of the pump is indicated at 28 and driven from the crank disk 29 on the shaft 30. The pump is connected to deliver to the tank 3 by the conduit 31.

The film driving sprocket 32 is disposed in advance of the winding spindle 33 which has a friction driving means.

Between the driving sprocket and the immersing pulleys I provide a plurality of guide pulleys 34, 35 and 36 which support the film to permit its drying before it is wound. These drying reaches are of suitable length to permit this.

In the embodiment illustrated the motor 37 is mounted on the frame 1. A reduction unit designated by the numeral 38 is provided in order that the film may be driven at the desired speed. The speed is further reduced by the driving connections which comprise

the shaft 39 disposed longitudinally of the machine and connected to the unit 38 by the means of the sprocket chain 40 and the sprocket wheels 41 and 42. A jack shaft 43 is connected to the shaft 39 by means of the sprocket chain 44 and the sprockets 45 and 46. The jack shaft 43 is in turn connected to the driving sprocket spindle 47 by means of the sprocket chain 48 and the sprockets 49 and 50. The supporting rollers 51 are carried by the usual spring-tensioned arm 52.

10 The winding spindle 33 is connected to the jack shaft 43 through the friction disks 54 and is provided with a film supporting disk 15 55. A guide arm 56 is also provided carried by the support 57.

With the parts thus arranged the film is drawn from the spool on the spindle 18 through the coloring fluid and is supported 20 in proper relation therein by means of the immersing rollers so that the longitudinal portion only of the film is subjected to the coloring liquid, thus permitting the coloring or staining of films such as are described in 25 my above mentioned application having pairs of foreground and back ground pictures disposed in paired transverse relation on the film. The pairs of pictures are indicated at 58 and 59 on the film illustrated.

30 The finished film is conventionally illustrated in Fig. 5 with both foreground and background portions in colors. It will be understood that either may be tinted or colored.

35 My improved apparatus permits the rapid coloring of a longitudinal section of film and this may be done with very uniform results and with little attention on the part of the operator.

40 Having thus described my invention what I claim as new and desire to secure by Letters Patent is:

1. In an apparatus of the class described, the combination with a tank and means for 45 maintaining a constant fluid level therein, of a pivotally mounted frame overhanging said tank, a screw for lowering said frame into and lifting it from said tank, a threaded rest on the swinging end of said frame, immersing pulleys mounted on said frame with their axes in an inclined relation to the surface of the liquid in the tank, a supply spindle and supporting disk mounted on said frame to swing therewith, said supply spindle being 50 provided with a retarding brake, a frictionally driven winding spindle, work supporting and guiding pulleys interposed between said immersing pulleys and said winding spindle to support the work in drying reaches, and a work driving sprocket disposed in advance of said winding spindle.

60 2. In an apparatus of the class described, the combination with a tank and means for maintaining a constant fluid level therein, of a pivotally mounted frame overhanging said 65

tank, means for adjustably supporting said frame in said tank, immersing pulleys mounted on said frame with their axes in an inclined relation to the surface of the fluid in the tank, a supply spindle and supporting disk mounted on said frame to swing therewith, said supply spindle being provided with a retarding brake, a frictionally driven winding spindle, work supporting and guiding pulleys interposed between said immersing pulleys and said winding spindle to support the work in drying reaches, and a work driving sprocket disposed in advance of said winding spindle.

3. In an apparatus of the class described, the combination with a tank, of an adjustably mounted frame overhanging said tank, a screw for lowering said frame into and lifting it from said tank, a threaded rest on the swinging end of said frame, immersing pulleys mounted on said frame with their axes at an angle to the surface of the fluid in the tank, a work holder means on said frame, a winding spindle, work supporting and guiding pulleys interposed between said immersing pulleys and said winding spindle to support the work in drying reaches, and a work driving sprocket disposed in advance of said winding spindle.

4. In an apparatus of the class described, the combination with a tank, of an adjustably mounted frame overhanging said tank, means for adjustably supporting said frame in said tank, immersing pulleys mounted on said frame with their axes at an angle to the surface of the fluid in the tank, a work holder means on said frame, a winding spindle, work supporting and guiding pulleys interposed between said immersing pulleys and said winding spindle to support the work in drying reaches, and a work driving sprocket disposed in advance of said winding spindle.

5. In an apparatus of the class described, the combination with a tank, of an adjustably mounted frame overhanging said tank, a screw for lowering said frame into and lifting it from said tank, a threaded rest on the swinging end of said frame, and immersing pulleys mounted on said frame with their axes at an angle to the surface of the fluid in the tank.

6. In an apparatus of the class described, the combination with a tank and means for maintaining a constant fluid level therein, of a pivotally mounted frame above said tank, a screw for lowering said frame into and lifting it from said tank, a threaded rest on the swinging end of said frame, and immersing pulleys mounted on said frame with their axes in an inclined relation to the surface of the fluid in the tank.

7. In an apparatus of the class described, the combination with a tank and means for maintaining a constant fluid level therein, of a pivotally mounted frame above said tank,

means for adjustably supporting said frame in said tank, a threaded rest on the swinging end of said frame, and immersing pulleys mounted on said frame with their axes in an inclined relation to the surface of the fluid in the tank.

8. In an apparatus of the class described, the combination with a tank, of a pivotally mounted frame overhanging the tank, means for adjusting and supporting said frame on its pivot, and immersing pulleys mounted on said frame with their axes at an angle to the surface of the liquid in the tank.

9. In an apparatus of the class described, the combination with a tank, of a frame adjustably mounted above said tank, a screw for raising and lowering said tank, and immersing pulleys mounted on said frame with their axes at an angle to the surface of the fluid in the tank.

10. In an apparatus of the class described, the combination with a tank, of a pivotally mounted frame overhanging the tank, means for adjustably supporting said frame, and immersing pulleys mounted on said frame with their axes at an angle to the surface of the fluid in the tank.

In witness whereof I have hereunto set my hand.

30 JAKOB BURKHARDT.
